UNITED STATES PATENT OFFICE.

ROBERT A. REYNOLDS, OF DETROIT, MICHIGAN.

GRINDING-MILL.

1,046,019.

Specification of Letters Patent.

Patented Dec. 3, 1912.

Application filed January 26, 1912. Serial No. 673,602.

To all whom it may concern:

Be it known that I, ROBERT A. REYNOLDS, a citizen of the United States, residing at Detroit, county of Wayne, State of Michigan, have invented a certain new and useful Improvement in Grinding-Mills, and declare the following to be a full, clear, and exact description of the same, such as will enable others skilled in the art to which it pertains to make and use the same, reference being had to the accompanying drawings, which form a part of this specification.

This invention relates to grinding mills and has for its object novel means for quickly separating the grinding disks and also adjustable means for limiting the approach of the grinding disks to each other. This latter means operates in connection with a non-rotatable member, so as to avoid all friction.

In the drawings: Figure 1, is an elevation of the grinding mill partly in section. Fig. 2, is a longitudinal section of the emergency means for separating the disks, showing the means that limits the approach of the disks to each other. Fig. 3, is a longitudinal section of the emergency means for spacing the grinding disks, showing the means turned to cause the disk to separate from each other. Fig. 4, shows an alternative form of connecting the stub shaft with the main shaft, the bearing cages and washers being shown in section.

5 A, is a heavy cast iron base of the machine from which rise the journal bearings B and C, formed by the pillow blocks *b* and *c*. Each is provided with a cap plate, the pillow block *b* with a cap plate *d* and the pillow block *c* with a cap plate *e*. The cover plate *d* is provided with an obliquely set threaded bore 1, in which engages the set screw 2 to effect a purpose hereinafter described.

45 At one end of the base A, the casting forms an insheathing casing F, to which access may be had through the hole closed by the cover plate 3. Fastened to the cover plate 3 is the hopper 4, in which engages the vertical feed screw 5 that is held in position in the bearings 6 and 7. This feed screw is driven by a counter shaft 8 through a pair of worm gears 9 and 9^a. A pulley wheel 10 on the end of the shaft is driven 50 by the belt 11 from the main shaft. The

main shaft 12 is supported by the journal bearings B and C, above described, and enters the casing F at its center. It carries on its interior end, the grinder-head 13 upon which can be screwed a grinding disk 60 14. The feed screw 15 is fitted on a projecting stud portion 16 of the main shaft 12 and serves to draw the grain in between the disks where it is thrown over the disk surfaces by centrifugal force. The grinding disk 17 is screwed, or otherwise fastened to the cover plate 3, so as to be in registering position with the companion disk 14.

This grinding mill is of the type known as the single head mill, in which the grinding disk 17 is a stationary disk, while the grinding disk 14 is a revolving disk. The disk 14 is revolved at approximately twice the speed that the two disks are revolved in a double head grinding mill, so that approximately the same results are accomplished so far as the speed of the stones is concerned.

The main shaft 12 is arranged to slide lengthwise its bearings and is provided between the journal-bearings B and C with a driving pulley 18, upon which a belt connected with some source of power may be placed.

In Figs. 2 and 3, I have shown more in detail the parts of my emergency means for separating the disks. As it frequently happens that foreign things such as stones, are drawn in between the disks and tend to strip the ribs of the disks, it is imperative that some means for quickly releasing the disks be provided, otherwise harm would come to the grinding disks. To effect this purpose, I provide the following means:—18, is a bushing within the bearing A, intervening 85 between the bearing and the main shaft 12. At the end of the main shaft 12 are a number of rings or bearing cages 19, in which are arranged the ball-bearings 20, that serve 90 as thrust bearings. Washers 21 are interposed between the bearing cages and the main shaft 12 and between the bearing cages and the annular flange 22 of the sliding stub shaft 23. These washers, also, intervene between the cages of each set of 95 bearings. The annular flange 22 is in reality a buffer, and will be so designated for clearness. It has an offset portion or key 24 that engages in the key way 25 of the 100 cover cap *d*, so that the stub shaft 23 is held 110

from rotative movement, but allowed to slide lengthwise of the key way 25. A collar 26 integral with the sleeve 27, that engages about the stub shaft 23, serves as a stop for the strong spiral spring 28 which is confined between this collar 26 and the buffer 22. The compression of this spring is regulated by a threaded sleeve 29 that is threaded through the cap plate 30, which, in turn, is held to the bearing A and the cover plate D by screws 31. A lock nut 40 holds the threaded sleeve from undesired turning. A knurled circular head or hand-wheel 32, integral with the threaded sleeve 29, affords means by which the sleeve may be turned, so as to project the collar 26 inward, or allow it to approach closer to the end by reason of the spring expansion. This, it will be seen, readily adjusts the compression of the spiral spring 28 and consequently the yieldable pressure that is afforded to the main shaft 12. The cam-faced ring 35 is squared on to the stub shaft 23, which is at that point reduced in diameter and square in cross section. Opposite this ring, is a second ring with an opposed cam face and on the shaft between these two cam-faced rings, is a bushing 34 upon which turns the lever 36, having a ring terminal 37. A nut 38 is threaded into the end of the stub shaft 23 and holds the cam-faced rings and the lever terminal together.

When it is desired to separate the grinding disks, the lever 36 is given a quick turn downward to such a position as shown in Fig. 3. This brings the widened portion of the ring terminal 37 between the narrowed portions of the cam-faced rings, as shown in Fig. 3. This, of course, forces the ring 35 outward and hence pulls the stub shaft 33 with it, thereby, also bringing the main shaft with it by reason of a connection therewith. This connection consists either of an extension 24^a of the offset portion or key 24 (shown in Figs. 2 and 3) which engages in the annular race 24^b on the main shaft 12, or (as shown in Fig. 4, an alternative form) a spindle 50 extending from the center of the stub shaft 23 through the center opening of the bearing cages 19 and enters a center bore of the main shaft 12. The spindle 50 has an annular race 51 into which the pins or set screws 52 driven through the shaft 12 may project so that the shafts are connected together for endwise movement but not for rotative movement. Therefore, when the stub shaft 23 is drawn outward by the lever and cam-faced rings, the grinding disks 14 and 17 separate, as shown in Fig. 60 3, so as to give space enough to avoid injury from any foreign material.

It often happens that the grain in the hopper suddenly gives out, so that there is no more to be fed to the grinding disks and, 65 inasmuch as the shaft 12 is under a strong

pressure, amounting, in the type of grinder that I use, to about three hundred (300) pounds expansion in the spiral spring 28, it is urgent that some means for stopping the approach of the two disks to each other be provided; otherwise, when the grain is exhausted, if the operator is not wary, the disks will come together while one is stationary and the other revolving at a high speed and they will strip each other. To 70 avoid this, I provide the obliquely disposed set-screw 2 that projects down into the key way 25 and stops the movement of the buffer 22 by engaging against the offset portion or key 24, the groove 2^a being formed in 75 the key extension 24^a so that this set-screw may be turned into it. The location of this set screw in connection with the buffer is quite important, as it will be noted that it engages with a non-rotatable member so 80 that there is no friction as would be the case were the set screw to engage with the end of the feed screw 15, or the shaft 12 in which case, it would be likely to wear a hole in the end of these members on account of the very 85 high rate of revolution of the shaft 12.

By disposing the feed screw 5 in line with the direction of feed, any straw or other fibrous material that may be accidentally introduced into the hopper is forced forward into the grinder instead of being wound about the feed screw and clogging the feed.

What I claim is:—

1. In a grinding mill, the combination of 100 a grinding disk, a second grinding disk, a shaft for driving the latter slidably lengthwise, a non-rotatable and slidable buffer for forcing the shaft lengthwise, a stub shaft fastened to the buffer, a spring for yieldingly forcing the buffer, a set screw for limiting the range through which the buffer functions, and a threaded sleeve and a collar about the stub shaft for confining the spring at the end opposite the buffer and for adjusting the tension of the spring, substantially as described.

2. In a grinding mill, the combination of 105 a grinding disk, a second grinding disk, a shaft for driving the latter slidably lengthwise, a stub shaft terminating in an annular flange or buffer provided with an offset portion or key engaging a key-way, the said buffer being adapted to resiliently force the main shaft lengthwise, and having 110 a non-rotatable connection therewith, a spring adapted to expand against the buffer, and means for sliding the stub shaft, thereby, withdrawing the main shaft, and compressing the spring, substantially as described.

3. In a grinding mill, the combination of 115 a grinding disk, a second grinding disk, a shaft for driving the latter slidably lengthwise, a stub shaft terminating in an annular 120

flange or buffer provided with an offset portion or key engaging a key-way, the said buffer being adapted to yieldingly force the main shaft lengthwise, and having a non-
5 rotatable connection therewith, a spring adapted to expand against the buffer, means for sliding the stub shaft, thereby, withdrawing the main shaft and compressing the spring and a set screw that can be turned to
10 engage against the key, substantially as described.

4. In a grinding mill, the combination of a grinding disk, a second grinding disk, a shaft for driving the latter slidably length-
15 wise, a stub shaft terminating with an annular flange or buffer provided with an offset portion or key engaging in a key-way, the said buffer being adapted to yieldingly force the shaft lengthwise, and having a
20 non-rotatable connection therewith, a spring adapted to expand against the buffer, a threaded sleeve and a collar on said stub shaft adapted to support the opposite end of the spring and regulate its tension, means
25 for sliding the stub shaft, and a set screw projectable toward or capable of being withdrawn from the buffer to give a variable

range of action for the pressure, substantially as described.

5. In a grinding mill, the combination of 30 a grinding disk, a second grinding disk, a shaft for driving the latter grinding disk slidable lengthwise, an inclosed bearing into which one end of the shaft enters, a non-
35 rotatable buffer contained in said bearing, the said buffer having a non-rotatable engagement with the bearing and a connection with the shaft, a spring adapted to expand against the buffer so as to resiliently force the main shaft lengthwise, means for sliding 40 the buffer lengthwise in the bearing so as to bring the grinding disks into close proximity, or withdraw them from such position, and a set-screw projected through the bearing to form an adjustable limit for the buf- 45 fer and hence to limit the approach of the disks to each other, substantially as described.

In testimony whereof, I, sign this specification in the presence of two witnesses.

ROBERT A. REYNOLDS.
